[57] CLAIM

The ornamental design for a child's rocker, as shown and described.

DESCRIPTION

FIG. 1 is a perspective view of a child's rocker showing my new design;

FIG. 2 is a front elevational view thereof;

FIG. 3 is a back elevational view thereof; and

FIG. 4 is a side elevational view thereof.

The opposite side is a mirror image thereof.

FIG. 1

FIG. 2

FIG. 3

FIG. 4
